[57] **CLAIM**

The ornamental design for a rope chain pendant, as shown and described.

DESCRIPTION

FIG. 1 is an end elevational view of the rope chain pendant showing my new design;

FIG. 2 is a bottom view of the rope chain pendant of FIG. 1;

FIG. 3 is an end elevational view of the opposite link end of the rope chain pendant of FIG. 1;

FIG. 4 is a top view of the rope chain pendant with a segment (shown in phantom lines) of chain attached, of FIG. 1; and,

FIG. 5 is a side elevational view of the rope chain pendant (both sides being identical) of FIG. 1.

The broken line showing of a rope chain, in FIG. 4, is for illustrative purposes only and forms no part of the claimed design.
